(57) **CLAIM**

The ornamental design for, an automobile, as shown and described.

DESCRIPTION

FIG. 1 is a front elevation view of an automobile, showing our new design;

FIG. 2 is a top plan view thereof;

FIG. 3 is a right side elevation view thereof;

FIG. 4 is a left side elevation view thereof;

FIG. 5 is a perspective view thereof; and,

FIG. 6 is another perspective view thereof.

The rear elevation view is a mirror image of the front elevation view. The broken lines are for illustrative purposes only and form no part of the claimed design.
